UNITED STATES PATENT OFFICE.

LINUS STEWART, OF WASHINGTON, DISTRICT OF COLUMBIA.

MODE OF CONSTRUCTING SAW-PLATES AND SETTING TEETH THEREIN.

Specification of Letters Patent No. 12,493, dated March 6, 1855.

To all whom it may concern:

Be it known that I, LINUS STEWART, of the city of Washington, District of Columbia, have invented a new and Improved 5 Mode of Constructing Saw Plate and Teeth; and I do hereby declare that the following is a full and exact description thereof, reference being had to the accompanying drawings and the lines, notes, and references 10 marked thereon.

The nature of my invention is to construct a saw in such a manner that the bits or teeth can be made of tempered steel, so that they can be taken out, ground, sharpened, and put back again in their place.

15 *a, a*, are two plates of thin steel or other metal, between are riveted or otherwise securely fastened plates *b, b*, of iron or steel at equal distances apart, in the space or

mortise between the plates *b, b*, is put the 20 bit C, which is secured by means of key D, the bit C is made with flanches on the sides E, E, which projects slightly over the thickness of the plate to give clearance to the saw. 25

What I claim is—

The improved mode of constructing saw plate, and fastening of the bits therein, as described, that is the bits shall be so made and arranged with projections on each side 30 equal to the set of the saw and fastened therein with a key or other known modes of securing the same.

LINUS STEWART.
